UNITED STATES PATENT OFFICE.

REDUS D. DODDS, OF HUMBLE, TEXAS.

SAMPLING DEVICE.

1,319,325.

Specification of Letters Patent.

Patented Oct. 21, 1919.

Application filed April 2, 1917. Serial No. 159,246.

To all whom it may concern:

Be it known that I, REDUS D. Dodds, a citizen of the United States, residing at Humble, in the county of Harris and State 5 of Texas, have invented certain new and useful Improvements in Sampling Devices, of which the following is a specification.

This invention relates to new and useful improvements in a sampling device.

10 The object of the invention is to provide a device of the character described whereby samples of formation may be withdrawn from the bottom of the bore, during drilling operations.

15 In the process of boring a well it is often desirable to obtain samples of formation through which the drill bit is passing and the device herein described has been constructed for the purpose of obtaining such 20 samples without interference with, or stopping, drilling operations.

With the above and other objects in view the invention has particular relation to certain novel features of construction, operation 25 and arrangement of parts, an example of which is given in this specification and illustrated in the accompanying drawings wherein:

20 The figure shows a vertical sectional view 30 of the device.

Referring now more particularly to the drawings, the numeral 1 refers to a tubular member, the upper end of which is provided with a bail 2 to which the suspending cable 3 is attached. Within this member is a valve 4 which permits the fluid to pass upwardly therethrough but closes the said member against a downward passage of said fluid. The lower end 5 of the tubular member is reduced so as to pass through a central opening in the drill bit and threaded into the lower end of this reduced portion is the tool 6. The lower end of this tool is beveled,

forming a sharp cutting edge as 7. The device is let down into a well by means of the cable 3, the reduced lower end thereof passing through the drill bit and extending below said bit, the tool 6 penetrating the formation below said bit, and said formation being forced up into the hollow tubular member. Within the tool 6 are a plurality of flexible fingers 8 which project upwardly and are inwardly inclined. These fingers engage under the sample forced up into the tubular member and block the lower end of said member and secure the sample of formation therein so that the same may be lifted to the surface. Any suitable means may be employed for closing the lower end of the device which may be found practical, the fingers 8 being shown only for the purpose of illustrating one means of closing the same.

What I claim is:

A device of the character described including a tubular member having a fluid passage-way throughout its entire length, and whose lower end is reduced, and detachable, a gate valve within and controlling said passage-way and permitting the passage of fluid upwardly therethrough, a detachable boring tool of the same diameter and threaded onto said reduced end, the lower end of said tool being beveled outwardly so as to form an annular cutting edge, flexible fingers within 75 said tool whose lower ends are secured to the tool and whose upper ends are free and curved inwardly, and a bail by means of which said device may be suspended.

In testimony whereof I have signed my 80 name to this specification in the presence of two subscribing witnesses.

REDUS D. DODDS.
